(57) **CLAIM**

The ornamental design for a textured upright luggage case, as shown and described.

DESCRIPTION

FIG. 1 is a perspective view from the upper corner of the textured upright luggage case embodying my new design. FIG. 2 is a front elevation view of the textured upright luggage case shown in FIG. 1.

FIG. 3 is a left side view thereof.

FIG. 4 is a right side view thereof.

FIG. 5 is a rear elevation view thereof.

FIG. 6 is a top view thereof; and,

FIG. 7 is bottom view thereof.

For convenience of illustration, the texture patterned areas are understood to represent a texture which continues throughout the respective portions of the design.
